UNITED STATES PATENT OFFICE.

ALBERT E. NEWTON, OF WEST BARRINGTON, RHODE ISLAND, ASSIGNOR TO RHODE ISLAND LACE WORKS, OF WEST BARRINGTON, RHODE ISLAND, A CORPORATION OF RHODE ISLAND.

DESIGN FOR A LACE.

Application filed June 4, 1923. Serial No. 6,382. Term of patent 3½ years.

To all whom it may concern:

Be it known that I, ALBERT E. NEWTON, a citizen of the United States, residing at West Barrington, in the county of Bristol and State of Rhode Island, have invented a new, original, and ornamental Design for Lace, of which the following is a specification, reference being had to the accompanying drawing, forming part thereof.

The figure is a plan view of a piece of lace embodying my design.

I claim:

The ornamental design for a lace substantially as shown.

In testimony whereof I affix my signature.

ALBERT E. NEWTON.
